(57) **CLAIM**

The ornamental design for the autonomous electric sprayer,
as shown and described.

DESCRIPTION

FIG. 1 is a top, right perspective view of an autonomous
electric sprayer, according to an embodiment of the invention;

FIG. 2 is a right side view of the sprayer of FIG. 1;

FIG. 3 is a left side view of the design of FIG. 1;

FIG. 4 is a front view of the design of FIG. 1;

FIG. 5 is a back view of the design of FIG. 1;

FIG. 6 is a top view of the design of FIG. 1; and,

FIG. 7 is a bottom view of the design of FIG. 1.

Broken lines illustrate boundaries of the claimed invention,
and form no part thereof.
